UNITED STATES PATENT OFFICE.

ANTHONY VANDERVELD, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

DISPLAY-RACK.

1,113,386.

Specification of Letters Patent. Patented Oct. 13, 1914.

Application filed July 2, 1913. Serial No. 777,084.

To all whom it may concern:

Be it known that I, ANTHONY VANDERVELD, a citizen of the United States, and a resident of the city of Grand Rapids, in the county of Kent and State of Michigan, have invented certain new and useful Improvements in Display-Racks of which the following, taken in connection with the accompanying drawings, is a specification 10 fully disclosing the invention.

This invention relates to and is of particular utility in connection with rotating display racks of the kind and type used in stores for the exhibition of goods for sale, 15 and in particular this invention is an improvement in the construction shown in my former Patent No. 1,032,969, issued July 16, 1912.

In the construction referred to, it will be 20 noted that the rack structure is mounted in a case or cabinet and movable back and forth in the cabinet bodily to present the rack at the front of the case. Such rack is also rotatable when in forward position in 25 the cabinet to present different supporting portions thereof to front position for easy access and to display the goods carried thereby. Furthermore the rack is locked from rotation except when at front position 30 and after being drawn to front position and rotated, the rack is withheld from bodily movement into the case or cabinet until the rack has been located in a predetermined position with respect to the case or 35 cabinet. The construction which guides and limits the movements of the rack is necessary for the protection of the case or cabinet, usually consisting chiefly of glass, from contact with the rack whereby it may be 40 broken or marred.

Included in the locking mechanism is a 45 disk notched in its periphery to receive a roller carried by a lever, the lever being spring pressed to yieldingly retain the roller in one of the notches, such lever being released to permit movement thereof when the rack is in forward position but rigidly held against movement when the rack is away from front position. When in front position 50 the rack may be rotated, the roller coming out of the notch and running on the edges of the disk. It will be evident that the spring influencing the lever is stretched under this operation and that the roller

bears against the edges of the disk with 55 greater force than when it is located in a notch. It has been found that the pressure of the roller against the disk edges serves to cut and wear away the disk and make smooth operation of the device impossible. 60

It is the primary object of this invention to eliminate this objectionable feature, providing a locking means which will hold the rotating rack member yieldingly in position with a sufficient force to prevent aimless 65 movement thereof when it has been freed for rotation and which, when it is rotated, will automatically lessen the force of the pressure of the bearing parts against each other.

More specifically it is purposed to control 70 the roller carrying lever by yielding means such that when the roller is in the notch of the disk it will be held therein with the usual and necessary force, but when the rack is rotated and the roller is bearing 75 against the disk edges, the pressure of the roller on the disk will be lessened to a point much below normal pressure and just sufficient to carry the roller into the notches when they come into juxtaposition, instead 80 of increasing the bearing pressure of the roller as in the construction noted. And this lessening of pressure is accomplished automatically as the rack is rotated and the roller carried out of the disk notch. 85

For an understanding of the means by which these results together with others not specifically enumerated are secured, reference should be had to the accompanying drawings in which, 90

Figure 1 is a vertical section centrally of the case or cabinet and the rack located therein. Fig. 2 is a plan view of a part of the rack carriage and the locking means used in controlling the rotative movements 95 of the rack, said locking means being in position occupied when the rack has been partially rotated. Fig. 3 is a plan view of the rack carriage and the means for movably mounting it, together with the rack locking 100 means, the parts appearing in position occupied when the rack has been bodily moved to the front of the case. Fig. 4 is a view similar to Fig. 2 with the parts of the locking means in position occupied when the 105 rack is in retracted position within the case or cabinet. Fig. 5 is a front elevation of the display device embodying the invention,

parts being broken away to better show the construction.

Similar reference numerals refer to similar parts throughout the several views of the drawings.

The inclosing case or cabinet 1 is of any desired kind or type, and is shown as having a top 2, sides 3 and back 4, which may be of glass, the front of the case or cabinet 5 being closed by suitable doors (not shown), capable of permitting the opening of the case for access to its contents. The bottom 5 may be suitably secured in position and above it a distance the floor 6 of the case 15 is located between which and the case bottom the supporting carriage for movably carrying the rack may be conveniently located.

Secured above the base 5 is a frame for carrying the movable carriage, said frame comprising side members 7 formed of metal having flanged upper and lower portions 8 and 9 between which run the rollers 10 connected by suitable axles 11 on which rest the bearing portions 12 of the carriage, stops 13 on the carriage serving to maintain the rolling supports for the carriage in proper relation thereto. If desired, the front and rear portions of the side members 7 may be connected by cross pieces 14. To prevent any tilting or tipping of the rack and carriage as they are moved to and from position within the case, the rearwardly extending portion thereof may have secured thereto rollers 16 and 17 which bear upon the under surface of the upper flange of the track frame as will be evident, reference being had to Fig. 3.

As shown, the carriage has rising therefrom the pedestal portion 18 which is secured thereto by bolts 19. The pedestal has front and rear extending portions 20, formed as webs connecting the base portion of the pedestal with its bearing portion 21. The web portions 20 extend through a suitable slot 22 in the floor of the case, the bearing 21 above the floor being enlarged. A sleeve 23 having a bearing portion 24 at its upper end is secured within the bearing 21 and extends upwardly toward the top of the case or cabinet.

Passing through the sleeve 23 and the upper and lower bearing portions 21 and 24 is the upright shaft 25 which at its upper end 55 may have secured thereto the hub 26 from which project the arms 27 supporting at their outer ends rods 28 or equivalent devices for carrying garments or other goods to be displayed. Below the end of the shaft 60 25, the carriage has a supporting piece 29 preferably of hardened metal on which is sustained a hardened pin 30 attached to the lower end of the shaft 25, such hardened block and pin acting as an anti-friction bearing 65 for carrying the weight of the rack,

shaft and goods and permitting the ready rotation of the rack.

In this class of devices, when the rack is moved to its position within the case it is desirable that it be prevented from rotating 70 owing to the liability of the rack striking the case and breaking or marring it.

It is also desirable that the rack be freed for rotative movement when it reaches front position in the case, and that when so rotated it 75 be locked and prevented from having bodily movement into the case except when the rack bars are so positioned that injury to the case is avoided on accomplishing the bodily movement.

These ends are accomplished in 80 applicant's construction as shown by the following means: Secured near the lower end of the shaft 25 is a disk 31, which is pro-

vided with diametrically opposed notches or recesses 32 so related to the rods 28 of the 85 rack that when the recesses are positioned in a line parallel with the front of the case, the rods will be similarly positioned and can be moved into and out of the case or cabinet without liability of injury to the case or 90 cabinet by reason of contact with the rack.

Pivotedly mounted at 33 on the carriage and adjacent the disk is a lever 34 which I will term the locking lever. This lever carries a 95 roller 35 suitably supported thereon as by a bracket 36 as shown, which roller is adapted to engage either of the recesses 32. Also se-

cured to the carriage pivotally at 37 is a lever 38 which may be known as the lever catch. A spring 39 is attached at one end 100 to lever catch 38 and at its other end is at-

tached to a link arrangement, the specific structure of which will be hereinafter de- 105

scribed, in such manner that its normal influence is to move the roller carried by the locking lever into the recesses 32 whenever 110 the roller and a recess come into juxtaposition, and normally tending also to move the lever catch 38 about its pivot in a clockwise direction.

One end of the catch is provided 115 with a shouldered portion 40 which at cer-

tain times is adapted to be engaged by a lip 41 on the locking lever, the construction be- 120

ing such that when the lip 41 and shouldered portion 40 are engaged, the locking lever 115

will be locked from movement on its pivot 33, but when the lip 41 and shoulder are 125

disengaged, the locking lever is freed for movement on its pivot. This structure and 130

the functions defined as inherent therein will be clearly apparent by reference to Figs. 2, 3 and 4.

Mounted in fixed position and preferably on one of the side members 7 of the track frame is a trip member 42 having two finger 125

portions 43, 44 of unequal length and ex- 130

tending toward the path of movement of the carriage. The trip member is positioned in the path of movement of the end 45 of the lever catch whereby as the carriage is moved 130

from its rear position to its front position, the end 45 will pass by the finger 43 of the trip but will engage the longer finger 44 with the result that the lever catch will be moved counter clockwise and move the shoulder portion 40 thereof out of engagement with the lip 41 freeing locking lever 34 that it may have movement about its pivot. The position of the parts in Fig. 3 illustrates this action.

With the parts in position as indicated in said figure, and after the rack has been bodily moved to the front of the case or cabinet, it will be apparent that the rack 15 may be rotated upon its vertical axis by a pull thereon tending to such rotative movement, the roller 35 carried by the locking lever being forced out of the notch 32 against the action of the spring 39, the rack 20 then being permitted rotative movement in either direction and through any desired arc of rotation. When, however, a recess 32 comes opposite the roller 35, the roller will 25 enter such recess, and the rack parts will be in position to be moved back into the case without danger of striking the case and injuring it in any way.

When the rack is rotated so that the rods 28 thereof do not lie parallel with the front 30 of the case, and the roller 35 is forced out of the notches or recesses 32, the end portion 41 of the locking lever passes over and beyond the shouldered portion 40 of the lever catch this prohibiting the clockwise movement of 35 the lever catch, and with the end 45 of the lever catch between fingers 43 and 44 of the trip member, it is evident that the rack cannot be moved toward the rear until such position of the parts occurs that the roller 40 35 seats in one of the recesses 32. Accordingly it is evident that when the rack is rotated so that the rods 28 thereof would be liable to injure the case if the rack was bodily moved to the rear, the rack is locked 45 from such bodily movement, but when the rack is located with reference to the case so that such injury is not liable, it is permitted bodily movement but its rotative movement is prohibited. As a means of stopping the 50 forward bodily movement of the rack, suitable stops 46 are provided at the front of the case against which the carriage may strike as it is drawn forward.

The foregoing structure as described is 55 identical with that of my former patent heretofore mentioned. In such structure, however, the spring 39 is interposed directly between the locking lever 34 and the lever catch 38 and is under tension such that the 60 roller 35 bears against the edges of the recess with considerable force. When the rack is rotated the spring 39 is placed under increased tension owing to the movement of lever 34 when the roller 35 is carried out of a recess, and the roller bears with increased

pressure against the disk edges. In practice it has been found that the wear of the roller on the disk edges serves in comparatively short time to cause unevenness in the disk edges, cutting thereof, and in general a 70 ruining of the disk such that the rotation of the rack is accomplished with difficulty and with much objectionable binding and noises indicative of defective parts. In this invention it is proposed to eliminate the 75 pressure of the roller on the disk edges to a minimum, leaving only sufficient force acting to press the roller against the disk that the roller will enter the recesses 32 when brought in proper relation thereto, but at 80 the same time, the force acting to retain the roller in the recess once it is in such recess will be as strong as in the old structure if desired, or any other degree of strength wanted. To these ends the spring 39 secured at one end to the lever catch has attachment at its other end to a link 47 said link being perforated at one end as shown to permit the attachment. At its other end link 47 is pivoted at 48 to the free end of a 85 short link 49 pivotally mounted at 50 to the carriage. Secured between the end of the locking lever 34 and the free end of link 49 is another link 51 which has pivotal connection with locking lever 34 at one end and 90 pivotal connection at the pivot 48 with links 47 and 49. Normally with the rack positioned within the case and the parts of the locking mechanism in positions shown in Fig. 4, the roller 35 is seated in a recess 32, 95 link 49 lies almost in parallel relation to the front of the carriage, and the line of force of spring 39 passes in the direction of line X, the moment arm of such force about pivot 50 being equal substantially to the distance 100 between pivots 48 and 50. The moment of force tending to rotate the locking lever, therefore is equal to the force exerted by the spring multiplied by the moment arm and such arm being the maximum length, the 105 moment of force is at its maximum and the roller 35 is pressed with maximum force against the disk when seated in a recess 32. When the rack has been rotated and the 110 locking parts assume the position shown in 115 Fig. 2, the clockwise movement of the locking lever 34 caused by the roller 35 being forced out of a recess 32, operates the end of the lever to the front thereby causing link 51 to turn link 49 about its pivot 50, 120 until it takes a position substantially parallel with the side of the carriage. Link 47 is carried with link 49 and the spring 39 is placed under increased tension, but the line of its force is represented by line Y, and the 125 moment arm thereof about pivot 50 is the perpendicular distance from line Y to the pivot center. As shown, this moment arm is very short so that the moment of force tending to rotate locking lever 34 about its 130

pivot is small notwithstanding the increase of the force of the spring, owing to the greatly shortened moment arm. The force of the roller 35 bearing against the disk edges is lessened very materially, in fact to such an extent that it is scarcely appreciable. There is no destructive action between the roller and disk during the rack rotation, but when the roller comes into position adjacent the recess 32, the initial force is sufficient to cause it to start to enter the recess, and with its entrance the force increases on account of the continual lengthening of the moment arm of the spring force until when it is seated in the recess the force tending to retain it there is at a maximum.

I have shown and described a complete and operative embodiment of my invention in which the defects of my former construction are overcome, and the bearing force of the roller automatically lessened with the revolution of the rack. Various dimensional changes in the link and locking lever mechanism, or changes in the strength of the spring will permit of any desired bearing force of the roller against the disk either when in or out of the recesses. Also various modifications in the specific structure by which the results desired are secured may be resorted to without departing from my invention. I, accordingly, do not desire to be limited to the specific structure shown, which is diagrammatic and illustrative of the invention, but consider myself as entitled to all modifications in structure properly falling within the scope of the appended claims.

What I claim as new and desire to secure by Letters Patent is:—

40 1. In a device of the character described, a rack mounted for rotation, a disk connected to and rotatable with the rack, recesses provided in the disk edges, a lever mounted adjacent the disk and having means adapted to engage the recesses in the disk, a spring connections between the spring and lever whereby said means on the lever will be held against the disk either in the recesses or against the disk edges and will be held with greater force when said means is located in a recess than when the rack has been rotated and said means carried out of a recess.

2. In a device of the character described, a rack mounted for rotation, a disk connected to and rotatable with the rack, a plurality of recesses provided in the disk edges, a lever mounted adjacent the disk and having means adapted to engage any of the recesses, means connected with the lever to cause said means to normally engage against the disk edges either in a recess or against the disk edges between the recesses, said connection of the lever operating means including elements whereby the pressure of the

means carried by the lever against the disk is greater when in the recesses than when out of the recesses.

3. In a device of the character described, a rack mounted for rotation, mechanism associated with the rack for yieldingly holding the rack against rotation in a predetermined position, and means included in such mechanism for diminishing the force of the holding means acting on the rack when the rack has been rotatably moved from such predetermined position.

4. In a device of the character described, a rack mounted for rotation, mechanism associated with the rack for yieldingly holding it against rotation in a predetermined position, and elements included in such mechanism whereby upon rotative movement of the rack away from such predetermined position, the force of the holding means acting on the rack is automatically diminished.

5. In a device of the character described, a rack mounted for rotation, mechanism associated with the rack for yieldingly holding it in a predetermined position, said mechanism including a recessed disk mounted on and rotatable with the rack and a lever mounted adjacent the disk and having means to engage the disk edges, and means for lessening the pressure of such means against the disk edges automatically effected on rotation of the rack away from such predetermined position.

6. In a device of the character described, a rack mounted for rotation, a recessed disk mounted on and rotatable with the rack, means to engage against the disk edges either in the recesses or between the recesses, means causing said means to bear against the disk, and means to diminish the pressure of said means against the disk automatically effected by rotation of the rack, and disengagement of said bearing means from the recesses.

7. In a device of the character described, a support, a rack mounted for rotation on said support, a disk having recessed edges connected to and rotatable with the rack, a lever pivotally mounted on the support adjacent the disk and carrying means adapted to bear against the disk edges and seat in the recesses therein, a link mounted on the support for pivotal movement, a second link connecting the lever and the first link, a spring secured adjacent the support and having connection with the links such that its line of force passes through the point of connection of the links.

8. In a device of the character described, a support, a rack mounted for rotation on the support, a disk having recessed edges connected to and rotatable with the rack, a lever pivotally mounted on the support adjacent the disk and carrying means adapt-

- ed to bear against the disk edges and seat in the recesses therein, a link pivotally mounted on the support, a second link connecting said link and the lever and having 5 pivotal connection to each, a third link pivotally connected to the other links at their point of connection to each other, and a yielding tension means secured to said third link and exerting a pulling force thereon.
- 10 9. In a device of the character described, a support, a rack mounted for rotation on the support, a disk having recessed edges connected to and rotatable with the rack, a lever pivotally mounted on the support adjacent the disk and having means adapted to bear 35 against the disk edges and seat in the recesses therein, a link pivotally mounted on the support beyond the end of the lever and in front thereof, a link connection between the lever and link whereby when the means on the lever is in a recess of the disk said link lies substantially parallel with a line joining the recesses and when said means is out of the recesses the link lies in a position substantially at right angles to the first position, a yielding tension means, and means connecting said tension means to the link.
- 15 10. In a device of the character described, a support, a rack mounted for rotation, mechanism associated with the rack for holding the 40 rack against rotation in a predetermined position, and means included in such mechanism for diminishing the force of the holding means acting on the rack when the rack has been rotatively moved from such predetermined position.
- 20 11. In a device of the character described, a rack mounted for rotation, mechanism associated with the rack for holding the 45 rack against rotation in a predetermined position, and means included in such mechanism for diminishing the force of the holding means acting on the rack when the rack has been rotatively moved from such predetermined position.
- 25 12. In a device of the character described, a support, a rack mounted for rotation on the support, a disk having diametrically opposed recesses at its outer edges connected 50 substantially parallel with the longitudinal center line of the support, and a tension means connected with the link tending to turn it about its pivot.
- 30 13. In a device of the character described, a support, a rack mounted for rotation on the support, a disk having diametrically opposed recesses at its outer edges connected 55 substantially parallel with the longitudinal center line of the support, and a tension means connected with the link tending to turn it about its pivot.

In testimony whereof, I have hereunto affixed my signature in the presence of two witnesses.

ANTHONY VANDERVELD.
